CHAIR SEAT

Henry P. Nordmark, Grand Rapids, Mich., assignor to American Seating Company, Grand Rapids, Mich., a corporation of New Jersey

Application October 3, 1938, Serial No. 232,952

5 Claims. (Cl. 155—180)

The present invention relates to chair seats; and its object is to provide an improved chair seat comprising a lower or base member and an upper member carrying the upholstery of the seat, said members being detachably connected so that they may be readily separated for repairing or replacing the same or the upholstery or other parts thereof; and further, to provide improved means for detachably connecting said members, and improved means for mounting and holding the upholstery securely in place.

This and any other and more specific objects hereinafter appearing are attained by, and the invention finds preferable embodiment in, the illustrative structure particularly described in the body of this specification and illustrated by the accompanying drawings, in which:

Figure 1 is a top plan view of the seat of a theatre chair or the like, the upholstery thereof being partially broken away to show parts underneath;

Figure 2 is a vertical sectional view thereof taken on line 2—2 of Figure 1;

Figure 3 is a vertical sectional view of forward parts of the same taken on line 3—3 of Figure 1;

Figure 4 is a vertical sectional view of rearward parts thereof taken on line 4—4 of Figure 1;

Figure 5 is a vertical sectional view of lateral parts of the same taken on line 5—5 of Figure 1;

Figure 6 is a fragmentary view in perspective of portions of the same;

Figure 7 is a view in perspective of portions of the chair, the seat's base or lower member and the seat's upholstery-carrying upper member being shown separated;

Figure 8 is an elevational interior fragmentary view of portions of the chair seat;

Figure 9 is a vertical sectional view thereof taken on line 9—9 of Figure 8.

In order to readily apply, remove or replace the upholstery of the seat of a theatre chair or the like, it is desirable to separate the part of the seat which carries the upholstery from other parts of the seat. To effect such ready separation, the illustrated seat comprises a concave lower member or "pan" 1 and an upper member 2 separable therefrom and carrying the upholstery 3. The pan 1, of sheet metal or the like, has an upwardly extending rim 4 with an inwardly extending flange or edge portion 5 curved inwardly-downwardly as shown.

The upper member 2 of the seat includes a 55

rigid frame 6 extending circuitously parallelly with the rim 4 and supported thereby, i. e. on the inwardly-downwardly curved edge portion 5 thereof. This frame 6 has an inwardly extending flange 7 with a downward extension 8.

The upholstery, comprising the flexible sheets 9, 10 and stuffing 11 therebetween is carried by the upper member 2 and is mounted adjacent the peripheral edges of the sheets on the downward extension 8 of the frame's inwardly extending flange 7, and may be folded at 12 around said extension's lower edge 13 and held in place thereon by clips 14 clamping the sheets on said extension as shown in Figures 8 and 9; or and preferably the upholstery is held in place by the spaced spurs 15 extending downwardly from said extension's edge and thrust through the peripheral edge portions of the sheets as shown in other views and particularly well shown in Figures 5 and 6.

Additionally to said clips or spurs or other means for mounting the upholstery on the upper member's frame 6, the upholstery in the assembled and connected position of members 1 and 2 is held in place by being clamped between said members, i. e. between the inwardly extending flange 7 of the frame and the inwardly-downwardly curved portion 5 of the rim 4 of the lower member 1. It will be seen that this clamping of the upholstery is augmented by the weight of the occupant of the seat.

The seat's said members 1, 2 are releasably held in connected or assembled position by suitable means, as the spaced outwardly extending, and outwardly-upwardly curved, arms 16 of the downward extension 8 of the frame's inwardly extending flange 7, these arms engaging and hooking under the lower edge 17 of the inwardly-downwardly curved upper edge portion 5 of the lower member's rim 4. Opposite these arms 16 the upper and lower members 1, 2 are releasably held connected by suitable means as the screw 18 extending at 19 through the rim 4 and threaded at 20 in the frame 6 as shown in Figures 4 and 7.

To yieldingly support or cushion the upholstery, springs mounted on the frame are provided, such springs 21 as shown being undulate and upwardly bowed. The end portions 22 of these 50 springs are inserted between the body 23 of the frame 6 and a clip portion 24 slit and pressed therefrom as best seen in Figure 5.

Downwardly bowed bars 25, mounted at their opposite ends 26 on the frame 6 and extending between the opposite sides of the seat and rest-

ing on the lower member or pan 1 medially thereof, serve to additionally support the frame 6 adjacent the ends of the springs 21. These bars being mounted on the frame 6 are removable with the upper member 2 from the lower member 1.

The seat may be mounted on a suitable supporting standard 27 in any desired way. In Figure 7 the lower member 1 is turnable on the horizontal spindle 28 whose vertical arm 29 is seated in a socket 30 in the standard's cross bar 31.

It will be seen that the upper member 2 of this seat may be readily disconnected and removed from the lower member 1; that these members being separated, the upholstery may be readily removed from the upper member for cleaning, repairing or replacement; that the upholstery is securely mounted on the upper member 2; that the upholstery is clamped adjacent its edges between said members 1 and 2; and that the frame 6 is additionally supported adjacent the ends of the springs 21 by bars 25 which are mounted on the upper member and removable therewith.

The invention being intended to be pointed out in the claims, is not to be limited to or by details of construction of any particular embodiment thereof illustrated by the drawings or hereinbefore described.

I claim:

1. A chair seat of the class described comprising a lower pan member having a closed bottom and an upwardly extending rim; an upper member including a frame removably supported upon said rim in parallel relation thereto, and upholstery mounted on the frame including a flexible sheet and means securing the sheet to the frame adjacent the edges of said sheet; detachable means securing said upper member upon said lower member; said sheet having its peripheral edges extending between the frame and the rim and clamped therebetween in the connected position of the upper and lower members; said upper member, with its upholstery and sheet, being removable as a unit from the lower member upon disengagement of the detachable securing means.

2. A chair seat of the class described comprising a lower pan member having a closed bottom and an upwardly extending rim; an upper member including a frame removably supported upon said rim in parallel relation thereto, and upholstery mounted on the frame including a flexible sheet, the frame having spurs extending through the sheet adjacent the edges of said sheet for securing said sheet to said frame; detachable means securing said upper member upon said lower member; said sheet having its peripheral edges extending between the frame and the rim

and clamped therebetween in the connected position of the upper and lower members; said upper member, with its upholstery and sheet, being removable as a unit from the lower member upon disengagement of the detachable securing means.

3. A chair seat of the class described comprising, in combination: a lower member having an upwardly extending rim; an upper member including a circuitous frame extending parallelly with the rim and removably supported thereon; upholstery mounted on the frame; springs yieldingly supporting the upholstery and mounted on the frame; and a bar extending transversely of the seat, connected with the frame and resting on said lower member medially thereof for additionally supporting the frame and the springs, the upholstery, the springs and the bar being freely removable with the upper member from the lower member in the separating movement of said members.

4. A chair seat of the class described comprising a lower pan member having a closed bottom and an upwardly extending rim; an upper member including a frame removably supported upon said rim in parallel relation thereto, and upholstery mounted on the frame including a flexible sheet and means securing the sheet to the frame adjacent the edges of said sheet; said upper member including also springs mounted on the frame for yieldingly supporting said upholstery; detachable means securing said upper member upon said lower member; said sheet having its peripheral edges extending between the frame and the rim and clamped therebetween in the connected position of the upper and lower members; said upper member, with its upholstery and sheet and springs, being removable as a unit from the lower member upon disengagement of the detachable securing means.

5. A chair seat of the class described comprising a lower pan member having a closed bottom and an upwardly extending rim; an upper member including a frame removably supported upon said rim in parallel relation thereto, and upholstery mounted on the frame including a pair of flexible sheets with padding therebetween, and means securing the sheets to the frame adjacent the edges of said sheets; detachable means securing said upper member upon said lower member; said sheets having their peripheral edges extending between the frame and the rim and clamped therebetween in the connected position of the upper and lower members; said upper member, with its upholstery and sheets and padding, being removable as a unit from the lower member upon disengagement of the detachable securing means.
